(57) CLAIM

The ornamental design for a wine bottle capsule, as shown and described.

DESCRIPTION

FIG. 1 is a front top perspective view of the wine bottle capsule of the present invention;
FIG. 2 is a front view thereof;
FIG. 3 is a back view thereof;
FIG. 4 is a left side view thereof;
FIG. 5 is a right side view thereof;
FIG. 6 is a top view thereof;
FIG. 7 is a bottom view thereof;
FIG. 8 is a bottom back perspective view thereof;
FIG. 9 is a bottom perspective view thereof; and,
FIG. 10 is a top perspective view thereof.
